ABSTRACT OF THE DISCLOSURE

An apparatus for using the energy dependence of the electron reflection coefficient to produce an electron beam having a narrower energy distribution than the original source beam by applying either a magnetic field alone or perpendicular electric and magnetic fields to force the electrons to undergo successive collisions with a reflecting surface.

CROSS-REFERENCES TO RELATED PATENTS

A patent application of even date herewith entitled "Apparatus To Control The Energy Distribution Of An Electron Beam" by William W. Hunt, Jr., has been filed in the U.S. Patent Office bearing Ser. No. 720,263 with a filing date of Apr. 10, 1968 which, for purposes of distinction, has been termed "Non-Magnetic Reflection-Type Electron Velocity Filter." The invention described herein has been described as a "Magnetic Reflection-Type Electron Velocity Filter." The "Non-Magnetic Reflection-Type Electron Velocity Filter" geometrically forces the electrons of a beam to undergo successive collisions with a reflecting surface by positioning the beam at a predetermined angle in relationship to the reflecting surface in order to provide a substantially narrower energy distribution than that in the original beam. The "Magnetic Reflection-Type Electron Velocity Filter" provides a substantially narrower energy distribution by applying either a magnetic field alone or perpendicular electric and magnetic fields to force the electrons of the beam to undergo successive collisions with a reflecting surface.

BACKGROUND OF THE INVENTION

This invention relates to apparatus for controlling the energy distribution in an electron beam, and more particularly, to an apparatus using the energy dependence of the electron reflection coefficient to produce an electron beam having a narrower energy distribution than the original source beam.

Certain scientific research apparatuses require highly monoenergetic electron beams, such as in ionization, collision, and electron attachment experiments and electron diffraction devices. Monoenergetic electron beams also find applications in electron-beam devices such as electron microscopes, cathode-ray tubes, and various display devices (e.g. TV picture tubes, radar display tubes) whose resolving power is now limited by the energy/velocity spread in the electron beam. This invention solves the problem of how to produce low energy beams with very narrow energy/velocity distributions. The low-energy monochromatic beams produced by this invention can be accelerated or decelerated to whatever energy is desired.

SUMMARY OF THE INVENTION

The reflection coefficient R of a given surface for low-energy electrons (say for $E \leq 3-5$ ev.) is known to depend on the energy E with which the electrons hit the surface. Also, in this same energy range, the reflected electrons retain essentially all of their incident energy. (See Niedermeyer and Holzl, Phys. Stat. Sol. 11, 651, 1965.) The

2

reflection coefficient $R(E)$ expresses the probability that an electron striking the surface with energy between E and $E+dE$ will be reflected rather than absorbed.

If a beam of electrons having an energy distribution $I(E)$ such that $I(E)dE$ is the number of electrons crossing a plane normal to the beam current per unit time with energy between E and $E+dE$ and such that the total beam current is

$$I_0 = \int_{E=0}^{\infty} I(E)dE$$

is caused to strike a surface then some of the beam will be reflected and some will be absorbed. The reflected current is given by

$$I_1 = \int_{E=0}^{\infty} R(E)I(E)dE$$

and the energy distribution of the reflected electrons is now $R(E)I(E)$, that is, the number of reflected electrons crossing a plane normal to the reflected beam current with energy between E and $E+dE$ is $R(E)I(E)dE$. If the reflected beam is in some way forced to impinge again on the same surface, then the current after this second reflection will be given by

$$I_2 = \int_{E=0}^{\infty} R(E)^2 I(E)dE$$

and the energy distribution of the electrons in this now twice-reflected beam is $R^2(E)I(E)$. Similarly, after n , such reflections the current is

$$I_n = \int_{E=0}^{\infty} R(E)^n I(E)dE$$

and the energy distribution is $R^n(E)I(E)$.

If the reflection coefficient undergoes maxima and minima as the incident energy (velocity) is increased from zero, then the electron energy (velocity) distribution of a multiply-reflected (diffracted) beam will have sharply defined peaks at energies (velocities) corresponding to each maxima in R overlapped by the initial energy (velocity) distribution. If the positions of these maxima in R are known in advance, then the original energy (velocity) distribution can be shifted by means of accelerating or retarding voltages to give significant overlap with only one of the maxima. In this case, the energy (velocity) distribution of the multiply-reflected electrons will be sharply peaked at the one energy (velocity) corresponding to this maximum, and the sharpness of the peak will increase as n , the number of reflections, is increased. Even if R has no maxima the energy (velocity) distribution of the reflected electrons will become sharper and sharper at that energy (velocity) corresponding to maximum overlap of R and $I(E)$.

In accordance with the present invention an apparatus exploiting this selective characteristic of successive reflections may be constructed in the following way: an appropriate reflecting surface (e.g. a flat sheet of metal) is mounted in a vacuum system such that the surface is parallel in one direction, X , perpendicular in the other, Y , to an applied magnetic field—i.e. so that the normal, Y , to the reflecting surface is perpendicular to the magnetic field. A surface for applying an electric field perpendicular to the magnetic field is mounted opposite and parallel to the reflecting surface. Electrons having the desired initial energy (velocity) distribution are made to impinge on the reflecting surface. The magnetic field causes the reflected electrons to be curved back to hit the surface again and again—the number of reflections being determined by the radius of curvature of the e^- 's in the magnetic field and by the length of the reflecting surface in the direction perpendicular to the magnetic field. If an electric field is applied by making the opposing sur-

face positive with respect to the reflecting surface, then the electrons follow trochoidal rather than circular trajectories and have their characteristic energy (velocity) distribution only at the plane of the reflecting surface. They travel the major portions of their trajectories at higher energies so that space-charge effects are lessened. In this case, the number of reflections can be varied by changing the electric field. The beam having the narrow filtered energy/velocity distribution is then extracted in any of a number of ways, the simplest being to allow it to pass through a slit (located exactly n times the distance between successive impacts beyond the point of initial impact) in the reflecting surface. In practice the n -times-reflected ribbon of monoenergetic electrons would be scanned to impinge on the center of the slit by varying the voltage applied to the field-forming plate or by varying the magnetic flux density.

An object of the present invention is to provide an apparatus for using the energy dependence of the electron reflection coefficient to produce an electron beam having a narrower energy or velocity distribution than the original source beam.

Another object of the present invention is to provide an apparatus to control and narrow the energy distribution of an electron beam by applying a magnetic field alone to force the electrons of the beam to undergo successive collisions with a reflecting surface.

Yet another object of the present invention is to provide an apparatus to control and narrow the energy distribution of an electron beam by applying perpendicular electric and magnetic fields to force the electrons to undergo successive collisions with a reflecting surface.

The various features of novelty which characterize this invention are pointed out with particularity in the claims annexed to and forming a part of this specification. For a better understanding of the invention, however, its advantages and specific objects obtained with its use, reference should be had to the accompanying drawing and descriptive matter in which is illustrated and described a preferred embodiment of the invention.

DESCRIPTION OF THE PREFERRED EMBODIMENT

Description of the drawings

FIG. 1 is a preferred embodiment of the invention, taken along line 1—1 of FIG. 2; and

FIG. 2 is a front view of the preferred embodiment shown in FIG. 1.

Now referring to FIG. 1, there is shown electron beam source 1 having variable voltage source 8 connected thereto to provide a variable control of electron beam 2. Electron beam source 1 is conventional and may be of the type utilized in cathode ray tubes. Electron beam 2 is comprised of low-energy electrons. In electron beam source 1, there is shown voltage source 14 providing voltage by way of transformer 15 for heating filament 16 which thereupon provides a low energy electron beam emerging from slot 17.

An appropriate reflecting surface 4 is provided by utilizing flat metal sheet 3 which is positioned such that the normal, Y, to reflecting surface 4 is perpendicular to an applied magnetic field B (everywhere perpendicular to and directed into the plane of the single drawing) that is provided by current flowing through solenoid 7. Flat metal sheet 3 is grounded. Flat metal sheet 3 includes input slot 3a and output slot 3b, and its surface opposite source 1 is the reflecting surface 4.

Parallel surface 9 is provided by utilizing flat metal sheet 10. Sheet 10 may also be grounded (see below).

Parallel surface 9 is used for applying an electric field perpendicular to the aforementioned magnetic field. The electric field is provided by connecting the positive side of variable voltage source 11 to metal sheet 10 and grounding the negative side thereof. Variable voltage source

11 is variable from 0 to the values required for achieving the requisite electric fields. Electron source 1 and metal sheets 3 and 10 are mounted in the conventional vacuum systems utilized, for example, in cathode ray tubes. Solenoid 7 and variable voltage sources 8 and 11 may be mounted in the conventional manner externally to the vacuum system. Metal sheets 3 and 10 are positioned in the vacuum system in a manner conventional to the cathode ray tube technique.

Now referring to FIG. 2, there is shown a view of FIG. 1 showing an applied magnetic field B provided by solenoid 7 parallel to the reflecting surface in the X direction.

In the operation of the apparatus referring to FIG. 1, electron source 1 is positioned so that electron beam 2 is directed through input slot 3a. Electrons having the initial energy (velocity) distribution characteristic of source 1 are made to impinge on the reflecting surface 4. The magnetic field, parallel to the reflecting surface in the X direction, causes the reflected electrons to be curved back to hit the surface again and again. The number of reflections being determined by the radius of curvature of the e's in the magnetic field and by the length of the reflecting surface. With an electric field also applied by making opposing surface 9 positive with respect to reflecting surface 4, then the electrons follow trochoidal rather than circular trajectories and have their characteristic energy (velocity) distribution only at the plane of reflecting surface 4. They travel the major portion of their trajectories at higher energies so that space charge effects are lessened. In this case, the number of reflections can be varied by changing the electric field by varying voltage source 11. The beam having the narrow filtered energy/velocity distribution is then extracted by allowing it to pass through output slit 3b located exactly n times the distance between successive impacts beyond the point of initial impact. In practice the n -times-reflected ribbon of monoenergetic electrons would be scanned to impinge on the center of slit 3b by varying the voltage to the field-forming plate 10 or by varying the magnetic flux density by varying the current flow through solenoid 7, by means of variable current source 12. Solenoid 7 is a conventional source or means for forming a magnetic field. In a different embodiment, the solenoid may be replaced by a permanent magnet.

It is noted that the magnetic field mode of operation may be utilized alone to obtain circular trajectories or the magnetic field in combination with an electric field is used to obtain trochoidal trajectories. To obtain exclusively magnetic field operation, voltage source 11 is eliminated or varied to obtain a zero voltage output and to obtain a combination operation of magnetic and electric field, voltage source 11 is increased to the desired magnitude.

Thus, there has been provided an apparatus wherein the original electron beam with a wide energy distribution has been controlled to provide a resultant electron beam with a substantially narrower energy distribution by the use of the energy (velocity) dependence of the reflection coefficient of a surface for slow electrons. This invention thereby solves the problem of how to produce low energy electrons beams with very narrow energy/velocity distribution. The low-energy monochromatic beams produced by this apparatus can be accelerated or decelerated to whatever energy is subsequently desired.

A constructive test using literature values of $R(E)$ for polycrystalline Pt (Niedermeyer and Holzl, Phys. Stat. Sol. 11, 651, 1965) combined with an initial energy distribution corresponding to normal component of a 3000° K. thermionic distribution accelerated by 0.1 ev. gave the reduced half-widths and attenuations indicated in the following Table I after 0, 3, 5, and 7 reflections. (Here $W_{1/2}(O)=0.175$ ev.) This is a severe test since neither the energy distribution nor this particular set of reflection data has maxima of the type discussed heretofore.

The half-width would continue to decrease if n were made larger.

TABLE I

n	$\frac{W_{1/2}(n)}{W_{1/2}(0)}$	$\frac{I(n)}{I(0)}$
	$W_{1/2}(0)$	$I(0)$
0-----	1.000	1.000
1-----	0.743	0.176
3-----	0.429	0.047
5-----	0.286	0.015
7-----	0.217	0.005

While in accordance with the provisions of the statutes, I have illustrated and described the best form of the invention now known to me, it will be apparent to those skilled in the art that changes may be made in the form of the apparatus disclosed without departing from the spirit of the invention as set forth in the appended claims and that in some cases certain features of the invention may be used to advantage without a corresponding use of other features.

Having now described my invention, what I claim as new and desire to secure by Letters Patent is as follows:

1. Apparatus to control and narrow the energy distribution of an electron beam comprising only first and second parallel surfaces, each having first and second ends, said first surface being a reflecting surface at ground potential and having an input and output slot at said first and second ends, respectively, a voltage source variable from zero to a preselected positive voltage magnitude to selectively apply an electric field between said first and second parallel surfaces varying from zero to a preselected magnitude, an electron beam source providing an initial

electron beam of low-energy electrons, said electron beam source being positioned to permit entry of said initial electron beam between the parallel surfaces through said input slot, means to apply a magnetic field parallel to and between said first and second parallel surfaces to force the electrons of said initial electron beam to undergo a predetermined number of successive collisions with said first reflecting surface along the length thereof to provide a resultant beam of substantially narrower energy distribution than that of said initial electron beam, said resultant electron beam being emitted at said output slot, said voltage source being set at zero for applying said magnetic field exclusively between said first and second parallel surfaces and to a predetermined positive voltage for applying a combination of said electric and magnetic fields between said first and second parallel surfaces.

2. Apparatus to control and narrow the energy distribution of an electron beam as described in claim 1 further including means to vary the intensity of said magnetic field to permit control of the number of successive collisions of said electrons with said first reflecting surface.
